UNITED STATES PATENT OFFICE.

LEO B. CRABBS, OF KANSAS CITY, MISSOURI.

ENGRAVING.

1,176,204.

Specification of Letters Patent. Patented Mar. 21, 1916.

Application filed February 6, 1914. Serial No. 816,974.

To all whom it may concern:

Be it known that I, LEO B. CRABBS, a citizen of the United States, residing at Kansas City, in the county of Jackson and

5 State of Missouri, have invented certain new and useful Improvements in Engravings; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to engravings, and more particularly to that class of engravings comprising monograms, initials, or the like, or to engravings consisting of one or more entire words; the principal object of the 20 invention being to provide fonts of engravings, the individual members of which may be assembled to form the subject matter of the engraving, and so arranged that the assembly lines may not be detected on the 25 printed card or sheet. In accomplishing this object I have provided improved details of structure, the preferred form of which is illustrated in the accompanying drawings, wherein:—

30 Figure I is a perspective view of a number of independent engraved members assembled for use in printing initials, and showing the mounting of the members on a chuck block. Fig. II is a detail perspective 35 view of one of the engraved members. Fig. III is a cross-section of a number of assembled members.

Referring more in detail to the parts:—

1 designates the individual engraved members, each of which is formed from a piece 40 of suitable material, having a letter, or the like, engraved in one of its faces. Each of the members 1 has a dove-tailed groove 3 at one longitudinal edge and a dove-tailed 45 rail 4 at the opposite longitudinal edge. The grooves and rails of all of the individual engraved members in each set or font are

alike and adapted for close locking coöperation in order that the edges of the engraved faces may fit closely and snugly to 50 prevent ink from entering therebetween.

In using the invention, presuming the possession of a font or set of engraved members of the character described, when it is desired to print a card or sheet by the engraved method, the proper character members 1 are selected and assembled by establishing the dove-tailed slot and rail connection therebetween, with the engraved characters in the proper sequence. The assembled members 1 are then secured to an ordinary chuck block, or the like, and the engraving process performed in the usual manner. After the printing has been completed, the engraved members are removed 65 from the chuck block and disconnected by sliding the members from each other over the dove-tailed joints and the individual members returned to their proper cases for use at a future time. 70

It is apparent that by providing the font of engraved members a great many combinations may be arranged quickly and without the necessity of engraving the steel or other base for each individual order for engraved work. 75

Having thus described my invention, what I claim as new therein, and desire to secure by Letters-Patent, is:—

The combination of individual character 80 blocks, each block having an undercut groove on one side thereof and a tongue on the other side thereof, said grooves and tongues adapted to bring and hold the separate blocks in close engagement so that the 85 surfaces on which the engravings are made may be continuous.

In testimony whereof I affix my signature in presence of two witnesses.

LEO B. CRABBS.
